KNITTING MACHINE AND METHOD OF
KNITTING

Robert H. Lawson, Pawtucket, and Arthur N. Cloutier, Lonsdale, R. I., assignors to Hemphill Company, Central Falls, R. I., a corporation of Massachusetts

Application June 23, 1936, Serial No. 86,814

22 Claims. (Cl. 66—24)

This invention relates to improvements in knitting machines and more especially to fully automatic half hose machines, i. e., knitting machines wherein rib tops and plain legs are knitted as a continuation one of the other, i. e., without hand transfer.

In the drawings:

Fig. 1 is a view in front elevation of the circular base of the knitting machine and the parts mounted thereon;

Fig. 2 is a front elevational view in continuation of Fig. 1, showing the means for automatically controlling certain of the movements pertaining to the knitting of a complete stocking on one machine;

Fig. 3 is a fragmentary view in side elevation showing a pattern drum and levers in engagement therewith for timing certain of the machine operations;

Fig. 4 is a plan view of the mechanism shown in Fig. 3;

Fig. 5 is a view in rear elevation showing the driving connections for effecting the racking of the drums shown in Figs. 2, 3 and 4;

Fig. 6 is a fragmentary view taken along the line 6—6, Fig. 5;

Fig. 7 is a fragmentary detail view from the right of Fig. 5;

Fig. 8 is a view in elevation of a portion of the machine from the opposite side of the machine as compared with Fig. 3;

Fig. 8a is a detail view of the pawl and ratchet mechanism for effecting the knitting of the loose course;

Fig. 9 is a plan view showing means for imparting a shogging movement to the needle dial as well as means for adjusting the shogging movement;

Fig. 10 is a fragmentary plan view showing a portion of the shogging mechanism illustrated in Fig. 9;

Fig. 11 is a view similar to Fig. 10 but showing some of the parts in the position illustrated in Fig. 9;

Fig. 12 is a fragmentary elevational view partly in section corresponding in phase to Fig. 11;

Fig. 13 is a fragmentary sectional view taken along the line 13—13, Fig. 9;

Fig. 14 is a sectional view taken through the needle cylinder, needle dial, and cams for acting upon the butts of the dial needles;

Fig. 15 is a view showing means for moving the dial knitting cam with respect to the dial butts;

Fig. 16 is a plan view of the mechanism shown in Fig. 15;

Fig. 17 is a sectional view taken along the line 17—17, Fig. 15;

Fig. 18 is a plan view showing the dial cams as they would appear with the top cap removed;

Fig. 19 is a fragmentary and more or less diagrammatic view illustrating one and one rib knitting;

Fig. 20 is a view illustrating the knitting of one or more plain courses, i. e., on cylinder needles only while the dial needles are in retracted position, the cylinder needles being shown as drawing their stitches over sinkers;

Fig. 21 is a fragmentary view showing the parts at a later phase of the knitting cycle and when the dial has been shogged with respect to the cylinder needles;

Fig. 22 is a view illustrating the projecting of the dial needles after shogging and the theretofore inactive cylinder needles being elevated to enter the loops carried by the dial needles thereby effecting transfer of the stitches theretofore held by the dial needles to cylinder needles;

Fig. 23 is a fragmentary view in side elevation illustrating the knitting of one and one rib fabric and corresponding to Fig. 19; the view being taken along the line 23, Fig. 19;

Fig. 23a is a view similar to Fig. 23 but in front elevation;

Fig. 24 is a view similar to Fig. 23 but taken along the line 24, Fig. 20;

Fig. 24a is a view similar to Fig. 24 but in front elevation;

Fig. 25 is a fragmentary view illustrating the relative position of the dial and cylinder needles preparatory to transfer of stitches from the dial needles to the cylinder needles; the view being taken along the line 25, Fig. 21;

Fig. 25a is a view in front elevation of Fig. 25;

Fig. 26 is a fragmentary view showing the dial needles fully advanced and the cylinder needles being elevated to enter the stitch held by the dial needles, the view being taken along the line 26, Fig. 22;

Fig. 26a is a view in front elevation corresponding to Fig. 26;

Fig. 27 is a fragmentary view illustrating the relative positions of dial and cylinder needles preparatory to transfer of the stitch from the said dial to the cylinder needle;

Fig. 27a is a plan view corresponding to Fig. 27;

Fig. 28 is a view similar to Fig. 27 but showing the needles at a later phase of the knitting cycle;

Fig. 28a is a plan view corresponding to Fig. 28; Fig. 29 is a view similar to that shown in Fig. 28 but showing the dial and cylinder needles at a later phase of the knitting cycle when the cylinder needle has entered the loop held by the dial needle;

Fig. 29a is a plan view corresponding to Fig. 29;

Fig. 30 is a view of the dial and cylinder needles at a still later phase of the knitting cycle when the dial needle has shed its loop which is being held on the cylinder needle;

Fig. 30a is a view corresponding to Fig. 30;

Figs. 31-34a inclusive, are views similar respectively to Figs. 27-30a, but showing a greater shogging of the dial;

Fig. 35 is a developed elevational view showing cams for acting upon the needle butts and jack butts, during transfer, following rib knitting;

Fig. 35a is a detail view of a long jack and a part of the needle in association therewith;

Fig. 35b is a view similar to Fig. 35 showing a short jack and associated needle;

Fig. 36 is a view similar to Fig. 35 but showing the cams during the last transfer course, i. e., as certain of the cylinder needles are being elevated between projected dial needles to remove the stitches therefrom;

Fig. 37 is a fragmentary plan view showing connections for operating a sinker cam;

Fig. 38 is an elevational view showing the mechanism shown in Fig. 37;

Fig. 39 is a sectional view taken along the line 39-39, Fig. 37;

Fig. 40 is a view of a pattern drum with the cams thereon for timing the desired movements of the knitting instrumentalities;

Fig. 41 is a view similar to Fig. 40 but showing another drum on the same cam shaft;

Fig. 42 is a small scale view in side elevation of the cam drum shown in Fig. 40;

Figs. 43-49 inclusive, are views showing different rows of cams shown in Figs. 40 and 41;

Fig. 50 is an elevational view partly in section showing the pawl and ratchet mechanism for effecting the movements of auxiliary pattern drums;

Fig. 51 is a fragmentary detail view showing the pawl and ratchet illustrated in Fig. 50 at another phase of the knitting cycle; and

Fig. 52 is a view showing a stocking or half hose knitted in the manner hereinafter described.

The machine includes a so-called circular base 1 in which is mounted, preferably, for rotary movements, a needle cylinder 2. Stand 3 has pivotally mounted therein a series of levers 4 which act upon yarn guides 5 in the usual manner. A cam block 6 is shown as mounted upon a stationary cam ring 7. The yarn guides 5 are pivotally mounted in a latch ring 8 in the usual manner, said latch ring being pivoted at 9 to an upright 10 which is supported by the circular base 1. Rising from the circular base 1 are uprights 11 supporting at the upper ends thereof a plate 12 in which is rotatably supported a dial shaft bearing 13.

Dial mechanism, Figs. 1 and 9-18 inclusive

Mounted upon the plate 12 is mechanism for effecting a shogging movement of the needle dial 14 for a purpose hereinafter to be described. The dial 14 is made to turn with a shaft 15 by means of a key 16. To the upper end of the said shaft 15 is made fast a plate or disc 17, a screw 18

passing through a hub 19 of the said disc 17 to connect it to the shaft 15. Depending from the disc 17 is a lug 20 which during rib knitting is maintained in a position shown in Fig. 9 by means of a detent constituted by a lever 21 pivotally mounted upon an arc shaped plate or strip 22, the latter being adjustably fastened to a gear 23. The lever 21 is notched as at 24, the notch being in engagement with the adjacent edge of the lug 20 as shown in Figs. 9 and 11. The lever 21 is urged to the position shown in Figs. 9 and 11 by spring 25, the arm of the lever 21 which engages the lug 20 being limited in its movements in that direction by means of a pin 26 which engages in a notch of the lever 21. When rib knitting is changed to plain knitting, the dial needles are shogged with respect to the cylinder needles in a manner hereinafter to be described, such shogging movement of the dial needles being effected by a forked lever 27 which is pivoted at 28 to a bracket 29 fastened to the plate 12. One hardened portion 30 of the fork of lever 27 is beveled at its end, said beveled end engaging a beveled end of the outer arm of the lever 21 thus rocking the lever 21 on its pivot and against the tension of the spring 25 thereby causing the said lever to be moved from the position shown in Figs. 9 and 11 to the position shown in Fig. 10. The release of the lever 21 from engagement with the lug 20 permits said lug to move from the position shown in Fig. 9 to the position, Fig. 10, to engage the end of the screw 31 which passes through a bracket 32 forming part of the hub 33 of the gear 23. A similarly adjustable screw 31' engages the lug 20 during rib knitting to cause the said lug 20 and consequently the dial 14 to rotate in proper timed relation with the needle cylinder. When the lever 27 is actuated in the manner described to cause the portion 30 thereof to engage and release the latch or detent 21 from engagement with the lug 20, a brake 34 consisting of a pad of felt or other material, carried by the other portion of the fork constituting one arm of the lever 27, moves into engagement with the periphery of the disc 17 thus overcoming the momentum of the rotating dial 14 and effecting a quick shogging movement of the dial to such a position that the lug 20 is moved into engagement with the end of the screw 31 where it remains during the knitting of the leg. After the shogging of the dial has been effected in the manner hereinbefore described, the lever 27 is rocked to the position shown in Fig. 1 which releases the detent 21 to the action of its spring 25 thereby causing an adjacent edge of the said lever 21 to rest against the lug 20 where it remains during the knitting of the leg. The mentioned rocking movement of the lever 27 also releases the disc 17 from engagement with the brake 34. Conveniently, during the first reverse stroke of heel and toe knitting, the lug 20 moves back to the position shown in Fig. 9 whereupon the spring 25 causes the lever 21 to snap to the position shown in said Fig. 9 whereupon the said lug 20 is engaged in the said notch 24, the parts thus being in position for subsequent rib knitting.

Mechanism for effecting the retraction and subsequent projection of dial needles to effect stitch transfer, Figs. 1, 2, 4, 14-18 inclusive, and 47 and 48

To effect the transfer from rib knitting to plain knitting in a manner hereinafter to be

described, it is desirable that the dial needles be retracted during the knitting of one or more courses, preferably two, as indicated in Fig. 20. In order to effect a retraction of the dial needles at the desired time, the dial transfer cam 35 and the dial knitting cam 36 are elevated and moved out of the path of the butts of dial needles 37 some of which, i. e., those on the instep side, are shown as having long butts and the others as having relatively short butts.

The transfer cam 35 has a right-angled portion 38 extending upwardly therefrom to which is connected as by means of a screw 39, a sliding cam link 40 having an inclined slot 41 therein through which passes the shank of the screw 39. The screw 39 also passes through a longitudinally extending slot 42 in a plate bracket 43 fastened to the hub 44 which is part of and projects upwardly from the dial cap 45. The cam 35 is normally maintained in butt engaging position as by means of a spring 46 attached at one end to the screw 39 and at the other end to a screw 47 fast to the plate bracket 43. The mentioned link 40 has a longitudinally extending slot 48 midway the length thereof and received in the slot 48 is a screw 49. A spring 50 is attached at one end to a pin 51 which is carried by the link 40 and the other end of the spring 50 is attached to a second pin 52 fast to the plate bracket 43, the spring 50 thus serving to maintain the link 40 in the extreme left-hand position illustrated in Fig. 15. At certain times during knitting, as will be hereinafter described, the link 40 is moved from the position shown in Fig. 15 to a position to the right thereof and against the tension of the spring 50, such movement of the link 40 causing, as by means of the slot and pin connection 39 and 41, the elevation of the cam 35, that is to a position away from the butts 37 on the dial needles. To effect the desired movement of the link 40, a stud 53 projects from the end thereof remote from the slot 41. In engagement with the said stud 53 is one arm 54 of the bell crank lever pivoted on a rod 55 supported at its ends in collars 56 adjustably fixed on adjacent uprights 11, screws 57 retaining the collars in position on the said upright and other screws 58 locking the rod 55 in position. The bell crank 54 is retained in its axial position by means of collars 59 fixed at the shaft 55. To the other arm 60 of the bell crank lever is pivotally connected a downwardly extending link 61 which passes (Figs. 2-4) through a slot in a bracket 62 which is fastened to the machine frame. Link 61 terminates at its lower end in a toe maintained in engagement with drum 63 or a cam 64 thereon by means of a spring 65 one end of which is connected to a pin or screw 66 carried by bracket 62 and the other end of which spring is connected to the link 61 conveniently by means of a notch 67 in the said link 61.

The connections just described are duplicated for dial knitting cam 36, a link 40 engaging a bell crank lever 68 likewise pivotally mounted on the shaft 55 and having an arm 69 pivotally connected to depending link 70, the toe of which is maintained, by means of a spring 65 as described, in contact with the surface of the drum 63 or cams 71 or 72 mounted thereon.

Extensions 38 of the cams 35 and 36 are conveniently guided in slots or grooves 73 in the dial hub 44.

Eccentric mounting of the dial with respect to the cylinder

As indicated in Fig. 14 by the dot and dash lines 74 and 75, the needle dial is slightly eccentrically mounted with respect to the needle cylinder, the dot and dash line 74 representing the dial axis and the dot and dash line 75 representing the axis of the cylinder. The purpose of the eccentric mounting of the dial with respect to the cylinder will hereinafter be described.

Mechanism for varying the extent of the shogging movement of the dial with respect to the cylinder, Figs. 9-12 inclusive

Adjustment of the screw 31 effects a variation of the shogging movement imparted to the needle dial. The position of the screw 31 as shown in Fig. 9, permits a shogging of the dial the distance of the two dial needles the effect of which is illustrated in Figs. 31-34a inclusive. By moving the screw 31 forwardly, movement of the lug 20 and consequently of the needle dial, upon release of the detent 21 hereinbefore described, limits the shogging of the needle dial to the distance between adjacent dial needles only, i. e., one dial needle shogging, the effect of which is illustrated in Figs. 27-30a inclusive.

Dial and cylinder connections, Figs. 1, 9, 10, 13 and 14

As herein disclosed, the needle cylinder 2 and the needle dial 14 rotate during circular knitting and reciprocate as during the knitting of heels and toes, the cams for acting upon the cylinder needles and jacks and the dial cap for acting upon the dial needle being stationary. In the knitting of rib fabric, it is essential that the needle cylinder and needle dial rotate together so that the dial and cylinder needles shall be maintained in proper relation with respect to each other.

As hereinbefore stated, the needle dial 14 turns with the shaft 15 due to the keyway connection 16. The dial 14 may be adjusted vertically with respect to the shaft 15 as by means of a screw 76 the end of which engages against a flat portion 77 of the shaft 15. The shaft 15 is supported for rotary movements on a bearing constituted by the sleeve or hollow shaft 13 which extends upwardly through the stationary plate 12. Adjacent to its upper end the shaft 13 is provided with a keyway 78 (Fig. 13), in which is engaged a key 79 forming part of ring 80 adjustably connected to a hub of the plate 12 by means of pin and slot connections 81. The slot 78 connects with a transversely extending slot (not shown) which forms in effect a bayonet slot which permits the needle dial and dial cap to be elevated by manual engagement of a wheel 82 which is connected to the upper end of the shaft 15 and then by turning the wheel 82 to retain the needle dial and dial cap in elevated position.

Rotary and reciprocatory movements of the gear 23 impart corresponding turning movements to the connected bracket 32 and consequently to the disc 17 and shaft 15 and thus to the needle dial 14. Screw 83 passing adjustably through the disc 17 limits the downward movement of the said disc, shaft 15 and parts connected thereto, by engagement with the upper surface of the bracket 32.

The gear 23 is conveniently driven by means of a gear 84 which is connected to a shaft 84' which extends downwardly and is driven by the usual ring gear (not shown) which is connected to and forms part of the needle cylinder 2.

Mechanism in connection with the knitting of the high splice and double sole, Figs. 1, 5, 8 and 9 inclusive

It is desirable, especially during the knitting of the double sole and high splices, that the dial, dial cap, etc., be elevated to permit the floating of the double sole yarn or yarns below the dial. To effect the necessary elevation of the dial, dial cap, etc., there is provided (Fig. 9) a lever 85 pivoted intermediate its ends at 86 to a bracket 87 supported by and connected to plate 12. One arm of the said lever 85 has two wings adjustably connected as by screws 88 to an arc-shaped piece 89 each arm of which has diametrically disposed and inwardly projecting ends or rolls 90 which engage the under side of the disc 17. The other end of the lever 85 extends outwardly from the machine and to the said end is pivotally connected at 91 (Figs. 5, 8) a downwardly extending rod 92, the lower end of which passes through and is adjustably connected to a lever arm 93. The arm 93 is connected to a horizontally extending shaft 94 which is supported in the machine frame. To the extending end 95 of said shaft is connected a lever mechanism (not shown) which is in engagement with a cam drum (not shown) mounted on a shaft 97 likewise supported in the machine and mounted therein above the shaft 94.

The connections hereinbefore described for the double sole and high splice mechanism permit rotations of the shaft 97 to rock the shaft 94 and consequently move the link 92 to a downward direction to elevate the disc 17 through the connections hereinbefore described and including the pins or rolls 90. The elevation of the disc 17 elevates the shaft 15 and the needle dial, dial cap and connected parts. To insure a return of the needle dial, dial cap, etc., to the proper lowered position at the completion of the high splice and double sole, a spring (not shown) may be provided between the wheel 82 and the hub 19 of the disc 17.

Mechanism for effecting knitting of a loose course preparatory to changing from rib to plain knitting, Figs. 2, 5, 8, 8a, 41 and 48

Immediately preceding transfer of stitches from the dial needles to theretofore inactive cylinder needles, alternate cylinder needles and the dial needles knit rib fabric and the last course of such rib knitting, i. e., immediately preceding the transfer, is knitted loose, that is, the cylinder needles draw longer stitches than previously. This so-called loose course is of importance in connection with the subsequent shogging to effect the transfer, being especially necessary when shogging over two dial needles in a manner hereinafter to be described.

To effect the knitting of the loose course on the alternate cylinder needles the main cam shaft 97 is rotated. Upon the said cam shaft 97 is fixedly mounted the fashioning drum 98, cams of which determine the vertical position of the fashioning bracket 99 and consequently of the cam to determine the length of the stitches drawn by the cylinder needles. To effect the desired rotation

of the cam shaft 97 and consequently the vertical position of the fashioning drum 98, the usual pawl 100 which advances the shaft 97 and cams mounted thereon as dictated by lugs on a pattern chain C, engages teeth on the usual ratchet 101 fast on the cam shaft 97. However, four courses are ordinarily knitted between each racking of the ratchet 101 by means of its pawl 100 which would result, in the present instance, in four loose courses being knitted by the cylinder needles. In order to reduce the four courses to the single loose course desired, one of the teeth on the ratchet 101, specially designated by 101', is relatively short so that when engaged and advanced by the pawl 100, the appropriate plunger 102 in the fashioning bracket 99 while the drum 98 is advanced still rests on its cam 103, the drum 98 coming to rest just before the plunger or cam 102 moves off the end of the said cam 103. To effect the knitting of one loose course on alternate cylinder needles fashioning drum 98 is advanced during a portion of which movement the plunger 102 drops off the cam 103 and onto the surface of the drum 98 being then elevated by another cam on the drum 98 in line with the cam 103. The supplemental movement imparted to the drum 98 is due to the action of a pawl 104 engaging a lug 105 on a drum 106 fast to the shaft 97. The pawl 104 is pivoted at 107 to a lever 108 pivoted intermediate its ends to a bracket 109. The other arm of the lever is provided with a toe 110 maintained in engagement with cam 111 by means of a spring 112 one end of which is fastened to the pawl 104 and the other end to the machine flange. The cam 111 is carried by and moves with the "104" gear 113 which latter makes one complete rotation during four courses of knitting. At an appropriate time in the knitting cycle, advance of the cam 111 rocks the lever 108 and consequently advances the pawl 104 to contact the lug 105 which advances the drum 106 and consequently the shaft 97, and as a result thereof advances the fashioning drum 98 which is fixedly mounted on the cam shaft 97.

Sinker mechanism for facilitating the shogging transfer, Figs. 1, 15, 37, 38 and 39

It occasionally happens that one or more of the sinkers 114 may not move back due to the tension of the fabric and as a consequence thereof when the dial needles shog with respect to the cylinder needles to effect a transfer, the strands of the loops may be drawn over the nibs 115 of such sinkers and break. Also, the shogged loops may be unduly stretched and possibly broken by reason of the fact that the sinker nibs engaging over a loop would deflect the same from the normal straight upward inclination, thus unduly tensioning the said loop. Furthermore, such forwardly positioned sinkers would, by imposing greater strain on the fabric, unduly tension the stitches to be transferred.

To overcome these disadvantages sinker reTRACTING CAM 116 is withdrawn preparatory to imparting a shogging movement to the dial and such withdrawal is conveniently effected by movement of the lever arm 54, which is in engagement with the stud 53, Fig. 1, in a direction away from the needle cylinder and dial. The aforesaid swinging movement of the lever 54 permits retraction of the link 40, by means of the spring 50, and consequent movement of the transfer cam 35 to its operative position to project the dial needles for transfer. For this purpose, a lever 117 is maintained in engagement

with the lever 54 by means of a spring 118 conveniently fastened to the bumper post bracket 119. The lever 117 is pivoted to the bracket 119 at 120 and intermediate its ends has a depending pin 121 which engages in a slot 122 in an extension plate 123 which is fastened to the sinker cam 116, the extension 123 passing outwardly through a slot in the sinker cap 124. A pin 125, upstanding from the plate 123, is engaged by a leaf spring 126, which is fastened to the sinker cap 126 and normally maintains the sinker cam 116 in a forward position.

Retraction of the cam 116 in the manner just described withdraws the nibs 115 of the sinkers sufficiently to avoid the possibility of the shogged loops being drawn over the tops of the sinker nibs or under the same and resulting in breaking stitches.

Cam mechanism for controlling the movements of the dial needles, cylinder needles and jacks, Figs. 1, 2, 3, 4, 14, 18, 35, 36, 40, 45, 46 and 49

To effect the knitting of the stocking or half hose shown in Fig. 52, it is necessary specially to control the cylinder needles and at times the dial needles. For controlling the cylinder needles long jacks 127 and short jacks 127' are provided, the said long and short jacks being alternately arranged in the slots of the needle cylinder 2. Furthermore, except as hereinafter noted, the long and short jacks under the long butt cylinder needles have long butts and the long and short jacks under the short butt needles are provided with relatively short butts.

In Figs. 35 and 36 are shown cams for acting upon the cylinder needles 128 and jacks thereunder in a manner presently to be described. The cam ring 7 and supplemental cam ring 129 which is mounted upon the circular base, have mounted thereon respectively the cams for acting upon the butts of the cylinder needles 128 and cams for acting upon the butts of the jacks 127, 127'. Mounted directly upon the cam ring 7 are cams 130, 131 and carried by the cam block 6 are knitting cams 132 and 132', between which is a guard cam 133. Adjacent to the cam 132' is a slidably mounted cam 134 which cooperates in the knitting in a manner presently to be described. Radially movable cams 135, 136 are positioned at two levels, the cam 135 being at a position to elevate the short jacks 127' by engaging their butts 137 at one level while the cam 136 is at a lower elevation to raise the long jacks 127 by engaging their butts 138 at a lower level. In this connection it will be noted that the butts 137 travel along the path 139 while the butts 138 travel along the path 140. There is also a cam 141 which remains in fixed position and engages both the short and long butts of the short jacks.

The cams 135, 136 are slidably mounted (Fig. 1) in a cam block 142 which is made fast to the supplemental cam ring 129. The cams 135, 136 project outwardly through slots in the block 142 the ends of which cams are recessed or slotted to receive the ends of bell crank levers 143, 144, 65 which levers are pivoted on opposite sides of a U-shaped bracket 145, said bracket resting upon the upper surface of the bracket 142 and being fastened thereto.

To the other arms of the said bell crank levers 143 and 144 are respectively pivoted links 146, 147, each consisting of two adjustably connected parts, to the lower ends of which (Figs. 3, 4) are pivotally connected levers 148, 149 which have

toes in engagement with the surface of a drum 150 or cams 151, 152 and 153, 154 respectively.

The cam 134 is slidably mounted in the cam block 6', the sliding movements thereof being effected by means of a bell crank lever 155 (Fig. 1) which is pivoted to the cam block 6' and at its upper end has a slot for engagement with a pin or screw 156 which projects laterally from an extension 157 of the cam 134. Pivots connected to the other arm of the bell crank lever 155 is an adjustable link 158, the lower end of which is pivoted (Fig. 2) to a lever 159, the latter being pivoted intermediate its ends to an arm 160 projecting from the machine frame. The other arm of the lever 159 has pivotally connected thereto at 161 a depending rod 162 which passes through a slot in the bracket 62 which bracket is connected to and projects laterally from a portion of the machine frame. The toe of the rod 162 is maintained in engagement with the surface of the drum 63 or cams 164 thereon by a spring 65, said drum being fixedly mounted upon a shaft 163 upon which cam drum 150 is also mounted.

The point of the cam 134 (Fig. 36) normally rests in a recess 165 in cam 131, provision being made for permitting the needle butts to pass the said cam when moving from left to right, Fig. 36, as during reciprocatory strokes of heel and toe knitting. To provide for this movement of the needle butts, the cam 134 is pivotally mounted, being maintained in the position shown in Fig. 36 as by means of a spring 166, Fig. 1, one end of which spring is connected to pin 156 and the other end to a screw 167 which also serves as a pivotal mounting for the bell crank lever 155.

Mechanism for timing and controlling movements of certain of the cam drums, Figs. 2-8 inclusive, and 40-51 inclusive

As hereinbefore stated, cam drums 150 and 63 are fixedly mounted upon the shaft 163. Rotary movements of the shaft 163 and consequently of the drums 150 and 63 mounted thereon are effected by the ratchet 168 and pawl 169, the latter comprising two adjustably connected parts. A spring 170 maintains the pawl 169 in engagement with the teeth of the ratchet 168. The pawl 169 is pivotally connected at 171 to a crank arm 172 which is fixedly mounted upon a shaft 173 which extends along the rear of the machine, Fig. 5, said shaft being supported in a U-shaped bracket 174 which is fastened to the so-called oil pan 175 of the machine. To the other end of the shaft 173 is fixedly connected an arm 176 to which is pivotally connected at 177 an upwardly extending link 178 having adjustably and fixedly connected thereto an extension 179. A spring 180, fastened at one end to a pin 181 fast to and carried by the link 178 and at its other end to the oil pan 175, normally urges the link 178 in a downward direction. The portion 179 of the link 178 has a longitudinally extending slot 182 through which passes a shaft 183 to which are fixedly connected cams 184 and 185. A roll 186 projects laterally from the link portion 179, said roll being maintained in contact with the surface of the cam 184 by the spring 180. Elevation of the link 178 rotates shaft 173 thus rocking the arm 172 and causing the pawl 169 to be advanced. The cam 185 by engaging the upper edge of the link 178 assists the spring 180 in retracting the pawl 169.

The shaft 183 is supported in a bracket 187 which is in turn connected to the machine frame,

Connected to the end of the shaft 183 remote from the cams 184, 185 is a pinion 188 which meshes with the "104" gear 113. The gear 113 rotates once every four courses of knitting which effects a complete rotation of the shaft 183 during each course of knitting, there being one hundred and four teeth in gear 113 and twenty-six teeth in gear 188. As a consequence of the gearing just described, the pawl 169 is actuated once each course of knitting.

As hereinbefore stated, the cam drums 63 and 150 are fixedly mounted upon the shaft 163 and consequently the mechanism just described times and controls the movements of the said drums 63 and 150. As will be noted by inspection of Fig. 4, the end of the pawl 169 is wider than the teeth of the ratchet 168, the projecting portion of the end of the pawl 169 extending over into the path of the first row of cams on the drum 150, there being two cams in the said row, namely, 189 and 190. The pawl 169 continuously advances the shaft 163 and consequently the cam drums 63 and 150 once during each course of knitting until one of the cams 189, 190 comes under the end of the pawl 169, after which the reciprocating movements of the pawl 169 are idle ones, that is, the ratchet 168 is not then advanced by the said pawl.

To restart the drum is the function of the mechanism specifically disclosed in Figs. 2, 50 and 51. As hereinbefore stated, the cam shaft 97 is the so-called main cam shaft, the said cam shaft being intermittently rotated, and as a consequence thereof the drums thereon, by means of the ratchet 101 acting in conjunction with the usual pattern chain C and constantly advanced ratchet C'.

Mechanism to start auxiliary cam shaft 163 when the pawl 169 is resting on cam 189 or 190, includes a pawl 191 which is pivoted at 192 to the fashioning drum 98. A spring 193 which is also fastened to the said drum 98 serves to hold the pawl 191 in engagement with the surface of adjacent drum 63 or cams 194 or 195 which constitute the cam row on the drum 63 next adjacent to the drum 98. The pawl 191 rotates with the drum 98 and in its rotations comes into contact with the cams 194, 195, and by engaging them, advances the drum 63 and consequently the drum 150 until the pawl 169 is free of cam 189 or 190 whereupon the continuous oscillatory movements imparted to the pawl 169 as hereinbefore described causes the tip of the pawl to engage the teeth of the ratchet 168 and advance the drums 150 and 63.

During the process of knitting the stocking or half hose shown in Fig. 52, it is desirable that the pawl 191 be lifted above cam 194 so that the drums 63 will not be advanced until later when, upon continued rotation, the pawl 191 engages cam 195. To effect this control of pawl 191, a pawl lifter 196 is provided, said pawl lifter being pivoted to the fashioning bracket 99 at 197 and being normally maintained in a position against a stop 198, also connected to the fashioning bracket 99, by means of a spring 199. The pawl 191 advances with the rotation of the drum 98 and when coming underneath the pawl lifter 196, a notch in the pawl 191 provides a shoulder 200 which engages the hooked or bent end 201 of the pawl lifter thus causing the pawl to be elevated and move idly past the cam 194.

The main cam shaft 97, as hereinbefore stated, is advanced intermittently and thereby controls certain of the machine operations. The auxiliary cam shaft 163 and cam drums mounted thereon

control certain other operations of knitting especially relating to the knitting of the rib portion of the stocking and transfer and as it is necessary to conserve moves of the main cam shaft 97, the auxiliary cam shaft 163 is, at times, independently advanced as by means of the pawl 169. As a consequence of the independent rotations of the auxiliary cam shaft 163 it is obvious that some means must be provided to retime the cam shafts 97 and 163 so that at the beginning of each stocking or half hose the cam shafts 97 and 163 shall always bear the same circumferential relation with respect to one another. To accomplish the retiming and also to again advance the auxiliary cam shaft 163 and cams mounted thereon, when the pawl 169 has been idled as by either of the cams 189 and 190, is the function of the pawl 191.

Briefly, the cycle of operations of the pawl 191 may be described as follows: beginning from the position of the parts illustrated in Fig. 51, the pawl 191 is shown as being elevated above the lug 194 and thereafter continued rotation of the fashioning drum 98 causes the pawl to approach and finally engage the lug 195. The idling movement of the pawl illustrated in Fig. 51 and the following movements of the pawl conveniently occur immediately following the knitting of the heel. Upon engagement of the lug 195 by the pawl 191, the movements thereafter imparted to the main cam shaft 97 are transmitted to the auxiliary cam shaft 163 and cams mounted thereon, the two cam shafts then moving together until shortly before the dial knitting cam 36 is withdrawn when its follower engages and rides up cam 72. At such time in order to permit the said dial knitting cam to move out on the short butts it is necessary to permit the pawl 169 to advance the drum 63 sooner than would otherwise be the case and for this purpose the toe 202 of a lever 203 is permitted to drop into a recess 204 between adjacent pins 205 which project laterally from the ratchet 168. The lever 203 normally is in such a position as to restrict the racking movements of the pawl 169 to one tooth of the ratchet 168. The spaces 206 and 207 between adjacent pins 205 later permit the pawl 169 to advance the ratchet 168 the distance measured by two teeth first when the dial transfer cam is moved in over the short butts and right after that when it is moved out from the short butts. The cam 64 effects the in and out movements of the dial transfer cam 35.

The pawl limiting lever 203 which has a pawl rest 208 is shown as pivoted at 209 to the machine frame, a spring 210 which is attached at one end to the machine frame and at the other end to the lever 203 at 211, normally maintaining the toe 202 of the lever in engagement with the pins 205, or in the recesses 204, 206, 207. As hereinbefore stated, the pawl 191 engages the lug 195 and causes the drum 63 and auxiliary shaft 163 to move in time with the main shaft 97 and cam drums mounted thereon immediately following the knitting of the heel. The pawl 169 then moves the drum 163 forwardly of the pawl 191 during the knitting of the welt; thereafter the pawl 191 engages the lug 194 and consequently advances the drum 63 in time with the drums on the main pattern shaft 97 until during the transfer when the drum 63 is advanced with relation to the pawl 191 to such an extent as to move the lug 194 forwardly of the pawl 191 as a consequence of which, when the pawl 191 again gains with respect to the drum 63, it

is necessary for the pawl lifter 196 to raise the pawl 191 to miss the lug 194 and later engage the lug 195.

Stocking or half hose, Fig. 52

At the top of the stocking at P is represented the pull course for separating adjacent stockings immediately following which are shown two courses of rib fabric R. At W is represented a four-course welt knitted on intermediate cylinder needles, the dial needles holding their stitches during the knitting of these courses. The rib top RT follows the knitting of the welt subsequently to which the transfer courses T are knitted, said transfer courses being preceded by the knitting of a loose course LC to facilitate transfer. The leg L of the stocking and the remaining portions are knitted in any desired manner.

Dial and cylinder needle movements as illustrated in Figs. 18-30a inclusive

In Fig. 19 the dial needles 37 and the ever active cylinder needles 128 are shown as knitting one and one rib fabric of a thread 212 drawn through one of the guides 5, butts of the dial needles being shown as being retracted by a fixed cam 214 forming part of the dial cap 45.

In Figs. 20, 24 and 24a is illustrated the knitting of one or more courses by the intermediate cylinder needles while the dial needles hold their stitches, the said courses immediately preceding the shogging transfer. Fig. 21 illustrates the next phase of the knitting cycle when the dial has been shogged with respect to the cylinder needles. The jack cam 141 elevates the theretofore inactive cylinder needles and the following cam 135 completes the elevating movement of the needles. Between the initial elevation by the cam 141 and the final elevation by the cam 135, the dial needles are projected by the transfer cam 35, as indicated in Fig. 22. Also the elevation of every other needle by the cam 141 is illustrated in Figs. 25 and 25a. Fig. 26 illustrates the position of the dial and cylinder needles just before the raised cylinder needles have been elevated by the cam 135 but after the dial needles have been projected. In the foregoing description, reference was made to the fact that the needle dial and the needle cylinder are eccentric. This eccentricity is taken advantage of to make certain that the needles to be further raised by the cam 135 shall enter the loops of their companion dial needles. In Fig. 25a, the companion dial and cylinder needles are shown as being somewhat spaced whereas in Fig. 26a the same needles are shown in contact, this being due to the said eccentric mounting of the needle dial and needle cylinder as a consequence of which as they rotate in a counter-clockwise direction, the dial needles gain with respect to the companion cylinder needles to which the stitches are to be transferred with the result that the said cylinder needles positively enter the loops stretched over them by the shogging of the dial needles.

The effect of the eccentric mountings of the needle dial and needle cylinder is more or less diagrammatically illustrated in Figs. 27-30a inclusive. It will be noted that a cylinder needle, specially designated by the numeral 215, see Fig. 27a, is to enter the loop 216 held on the shank of the dial needle indicated at 217. Continued rotations of the needle dial and needle cylinder and the consequent projection of the dial needles 217 by the portion 218 of cam 35, causes the loop 216 to be moved over the ascending cylinder needle 215 and concomitantly spreads or opens the said loop 216 in a more or less horizontal plane. At the same time, i. e., between the phases indicated in Figs. 27a and 28a, each ascending cylinder needle 215 moves against the shank of the companion dial needle 217 and positively enters the loop 216 as illustrated in Fig. 28a. The spreading or opening of the loops is due in part to the shoulder 218' which not only moves the loop across the path of the needle 215 but also tends to open the loop for the reception of the said cylinder needle 215. Figs. 29 and 29a illustrate the parts at a still later phase of the knitting cycle where the dial needle has been moved a short distance further outwardly and the cylinder needle 217 has passed up through the spread loop 216. Thereafter, retraction of the dial needle by the cam 219 leaves a loop on the cylinder needle.

20 The transfer operation just described is repeated in connection with every dial needle and companion and theretofore inactive cylinder needles so that at the completion of the transfer all the dial loops are on the cylinder needles and all the dial needles are retracted to an inactive position where they remain throughout the remainder of the stocking.

25 The cylinder needles that knit the instep half or portion of the stocking or half-hose have long butts while the cylinder needles that knit the heel and toe have relatively short butts. Likewise the dial needles corresponding in position to the instep cylinder needles have long butts and the remaining dial needles relatively short butts; also 30 the long jacks underneath the long butt cylinder needles have long butts and the long jacks underneath the short butt cylinder needles have short butts. The first twenty of the short jacks under the short butt needles and likewise the first twenty of the short jacks under the long butt needles each have long butts and the remaining butts of the short jacks under the long and short butt needles have short butts. The long and short butts on the cylinder needles perform their 35 usual functions. The described arrangements of long and short butts both on the dial needles and jacks are solely for the purpose of permitting the dial cams 35, 36 and the jack cams 135, 136 to move forwardly against the short butts, first engaging the long butts and then while opposite the long butts moving forwardly to a position to engage the short butts.

Transfer from rib to plain knitting by two-dial needle shogging illustrated in Figs. 31-34a inclusive

As hereinbefore described, the position of the screw 31, Fig. 1, permits a two-dial needle shogging movement, the single-dial needle shogging movement just described in connection with Figs. 27-30a-inclusive, being effected by adjusting the screw 31 inwardly to limit the movement of the stud or post 20. In Fig. 32a a cylinder needle, specially designated by numeral 220, is to receive a stitch 221 carried by dial needle 222. The position of the needles shown in Fig. 31a corresponds to that shown in Fig. 27a excepting that the dial needle has been shogged twice the distance illustrated in Figs. 27-30a inclusive, otherwise the operation is the same, that is, Figs. 31-34a correspond respectively to Figs. 27-30a. A shoulder 223 on the dial needle 222 serves the dual function of spreading the loop 221 laterally and forcing the same for-

wardly to a position over the ascending cylinder needle 220.

In Figs. 31a, 32a, 33a and 34a as well as in the corresponding Figs. 27a, 28a, 29a and 30a, the arrows indicate the direction of movements of the needles, the shogging consequently being in a reverse direction.

Mechanism for controlling the movements of the lever 27, Figs. 1, 2, 3, 12, 41 and 44

The lever 27 including the brake 34 remains in the relatively elevated position shown in Fig. 1 throughout the knitting of the stocking excepting when it comes into play to effect the shogging of the dial at which time the said lever 27 is moved to the position shown in Fig. 12. To control and time the movements of the lever 27, a cam 224 is fastened to the cam drum 150 leaving a short space between the ends of the cam by means of which the lever 27 is permitted to move to the position shown in Fig. 12. Pivottally connected to the arm of the lever remote from the brake 34 is a depending link 225, said link consisting of adjustably connected parts. At its lower end the said link is pivotally connected to a lever 226 pivoted intermediate its ends 227 to the machine frame. As will be seen from inspection of the drawings, when the toe of the lever 226 is on the cam 224, the lever 27 is maintained in the elevated, inactive position shown in Fig. 1, whereas when the toe of the lever 226 drops off the cam 224 and rests on the surface of the drum 150, the lever 27 moves to the position shown in Fig. 12, and to insure this movement, a spring 228 is fastened at one end to the plate 12 and at its other end to a collar 229 adjustably fixed to the link 225.

Operation

The stockings or half hose are preferably knitted as string work, i. e., connected stockings, and as a consequence thereof the cycle of operation is repeated for each stocking or half hose. For convenience in the following description of the operation of the machine, the cycle shall begin with the knitting of the so-called loopers' rounds (not shown) which follows the knitting of the toe, the knitting proceeding from the top to the toe of the stocking or half hose.

The loopers' rounds are knitted by all of the cylinder needles, the dial needles being idle. Preceding the knitting of the pull course, it is desirable to knit anti-ravel courses A to remove the strain from the stitches thereafter to be dropped thus avoiding the likelihood of runs. To effect the knitting of the anti-ravel courses, alternate cylinder needles, i. e., the ones inactive during the knitting of rib fabric, knit four courses while the intermediate needles hold their stitches. Upon the completion of the knitting of the four courses by the alternate needles, the yarn guide 5 feeding yarn to the needles is elevated and remains elevated during the remaining four revolutions of the needle cylinder thus making certain that the loops shall be cast off the mentioned alternate cylinder needles. A so-called pull course P is then knitted, the alternate cylinder needles dropping their stitches while the intermediate needles knit one course. The pull course P is availed of to conveniently separate adjacent stockings or half hose. Two rib courses R are then knitted with all the dial needles and intermediate cylinder needles knitting. Following the knitting of the said two rib courses, four courses are knitted on the intermediate cyl-

inder needles, the dial needles holding their stitches thus knitting a welt W. Following the knitting of the said four courses, the dial needles are again projected to knit the rib top RT which extends down to the transfer T. To assist in the subsequent transfer operation by shogging the dial needles with respect to the cylinder needles, it is desirable to knit a relatively loose course on the cylinder needles and to effect this result the hereinbefore described pattern mechanism illustrated in Fig. 8a comes into play.

Subsequent to the knitting of the mentioned loose course on the cylinder needles, the transfer of the stitches from the dial needles to theretofore inactive cylinder needles is effected in a manner hereinbefore described with special reference to Figs. 19-34a inclusive. Immediately after the knitting of the loose course, and as part of the transfer operation, the dial needles are withdrawn, as illustrated in Fig. 20, while the intermediate cylinder needles knit two and one-half courses. Subsequent to the knitting of the transfer, the plain leg is knitted on all of the cylinder needles and the high splice, heel, foot, with or without a double sole, and toe are knitted in any desired manner.

During the knitting of the stocking as hereinbefore described, the dial transfer cam 35 and the dial knitting cam 36 are specially controlled in the following manner. During the knitting of the leg, etc., of the stocking down to the two rib courses R, the dial knitting cam 36 is maintained in an elevated position by the cam 71 on the drum 63 and to effect the knitting of the said two rib courses R the plunger 70 drops off the cam 71 resting on the surface of the drum 63 at 230. Following the knitting of the two courses, the dial needles are retracted to knit the four-course welt and to effect the necessary withdrawal of the knitting cam 36, the cam 72 elevates the plunger 70. Immediately following the knitting of the four-course welt, the dial needles are again projected to knit the rib top RT, this being accomplished by the plunger 70 dropping off the cam 72 and onto the surface of the drum 63 at 231. At the completion of the knitting of the rib top RT, the plunger 70 rides up the cam 71, and to effect the projection of the dial needles for transfer purposes as hereinbefore described, the plunger 61 operatively connected to move the transfer cam 35, drops off the cam 64 and onto the surface of the drum 63.

Modification

To avoid the knitting of two and one-half courses on the cylinder needles in connection with the transfer and as illustrated in Fig. 20, that is, to permit the knitting of the same number of such courses on the instep and heel cylinder needles, the dial needles may all have the same length of butts and a vertically movable collar which rotates with the dial needles may engage the tails of the dial needles opposite the instep needles and a corresponding and independently movable collar may engage the tails of the dial needle opposite the heel needles, then elevation of the dial butts to be engaged by a fixed cam may be timed so that just two courses will be knitted by all of the cylinder needles at the period of the knitting cycle indicated by Fig. 20.

A lug may extend upwardly from that portion of the lever 21 adjacent to the lug 20 to guide the said lug in its downward movements and prevent the same from hitting the top face of the

lever 21 as subsequently to high splice or double sole knitting.

Conclusion

In the foregoing description, the invention has been described in detail and one specific embodiment of the mechanism employed in carrying out the invention has been shown in the drawings; however, there is no intention thereby of limiting the invention to the precise details of construction described and shown otherwise than as determined by limitations in the claims.

We claim:

1. A knitting machine including a rotary needle cylinder and a rotary needle dial, the cylinder having twice as many needles as the dial, means for acting upon the needles to knit rib fabric and plain fabric the one a continuation of the other, means for imparting cooperating movements to the dial needles and the cylinder needles to effect a transfer of stitches from the dial needles to some of the cylinder needles, said means including a shogging mechanism for causing relative movement between the dial needles and cylinder needles to move loops to a position to be transferred directly from dial needles to cylinder needles.

2. A knitting machine having two opposed rotary needle beds and a driving connection between the two needle beds so that rotary movements imparted to one needle bed are imparted to the other also, means for breaking the said driving connection, in combination with a brake acting upon the dial rotary mechanism in such a manner as to retard movement of the dial and thereby effect a quick relative shogging of the needle cylinder and needle dial.

3. A knitting machine having a needle cylinder and a needle dial each having needles, in combination with cam means for acting upon the dial needles to cause them to knit, and other cam means for acting upon the dial needles to project the same to assist in transferring stitches to cylinder needles, means providing a driving connection between the needle cylinder and needle dial, in combination with means for temporarily breaking the said driving connection to effect a relative shogging movement between the needle cylinder and needle dial to position the dial and cylinder needles to effect stitch transfer without the aid of cooperating instrumentalities.

4. A knitting machine including a needle dial and a needle cylinder, means forming a connection between the needle dial and needle cylinder to prevent relative movements between them, means for controlling the needles in the dial and cylinder to knit rib fabric and thereafter plain fabric, the transition from rib fabric to plain fabric being effected by knitting a relatively loose course and thereafter imparting a relative shogging movement to the dial and cylinder needles and then moving the dial and cylinder needles in such timed relation that some of the cylinder needles remove the stitches theretofore held by the dial needles.

5. A knitting machine having a rotary needle dial and a rotary needle cylinder the axes of which are eccentric, means for effecting a driving connection between the needle dial and needle cylinder and means for temporarily breaking the driving connections, means for knitting rib fabric and plain fabric as a continuation thereof, in combination with means for imparting a relative shogging movement to the needle dial

and needle cylinder preparatory to the transition from rib to plain fabric, the eccentric axes thereafter acting to cause dial and their companion cylinder needles to which their stitches are to be transferred, to approach one another to facilitate transfer of the stitches from the dial needles to the cylinder needles.

6. A method of transferring stitches from needles of one set to needles of another set, said method including the elevating of needles of the second set to an overlapping position with respect to the path of the needles of the first set, thereafter projecting the needles of the first set and then continuing the elevating movement of the needles of the second set so that stitches on the needles of the first set are received by needles of the second set, and during the aforesaid needle movements causing needles of one of the said sets of needles to approach needles of the other set to ensure transfer of stitches from needles of the second set to needles of the first set.

7. A knitting machine having a needle dial and a needle cylinder there being more needles in the needle cylinder than there are in the needle dial, means for causing the needles to knit rib fabric and thereafter plain fabric and effecting a transition from rib fabric to plain fabric during the knitting of one or more courses, and means for imparting a relative shogging movement to the needle dial and needle cylinder and for thereafter causing relative movements to be imparted to the cylinder and dial needles to effect transfer of stitches directly from the dial needles to the cylinder needles without the aid of cooperating transfer instrumentalities.

8. A knitting machine having a needle dial and a needle cylinder and needles independently mounted in the said needle dial and needle cylinder, jacks positioned beneath the cylinder needles, an alternate set of jacks having certain characteristics and an intermediate set of jacks having other characteristics so that the said alternate and intermediate jacks can be independently controlled, means for acting upon one set of jacks to move their needles to effect the knitting of rib fabric in conjunction with interspersed dial needles, and means for acting upon the intermediate jacks to act upon and move the companion needles to assist the transfer of each stitch directly from each dial needle to the companion cylinder needle without the aid of a co-operating instrumentality.

9. A knitting machine having a needle cylinder and a needle dial and needles independently mounted therein, means for knitting rib fabric and plain fabric in continuation thereof by means of one or more transfer courses, means to assist in the transfer, said assisting means including a cam partially to elevate theretofore inactive cylinder needles, the construction and operation being such as to cause a dial needle from which a stitch is to be transferred and a cylinder needle to which the said stitch is to be transferred to approach one another, and another cam to project companion dial needles.

10. A knitting machine having a needle dial and a needle cylinder and needles independently mounted therein, means for effecting a transfer from rib fabric to plain fabric, the said means including a transfer cam for projecting the dial needles and two spaced cams elevating cylinder needles to receive stitches from the dial needles, the first of said two cams elevating cylinder needles prior to projecting of the dial needles beyond the cylinder needles, the construction and

operation being such as to cause a dial needle from which a stitch is to be transferred and a cylinder needle to which a stitch is to be transferred to approach one another, the other of the said two cams then further elevating the cylinder needles after the dial needles have been projected to a position adjacent to the cylinder needles.

11. A knitting machine having a series of dial needles and a series of cylinder needles and means for shogging one series of needles with relation to the other to effect a transfer of stitches from one series of needles to the other series of needles, sinkers for cooperating with one series of needles during plain knitting, in combination with means for moving the sinkers out of position so as not to interfere with the shogging.

12. In a knitting machine having two circular needle beds mounted for rotary movements, rib needles in one of the said needle beds and plain needles in the other said needle bed, means for controlling both sets of needles to knit rib fabric and one set of needles only to knit plain fabric, in combination with means to effect transfer of stitches from rib needles to plain needles, said means including an eccentric mounting of one needle bed with respect to the other, the construction and operation being such that transfer of the stitches from rib needles to plain needles is facilitated by the eccentric mounting of the two needle beds causing, during rotations of the two needle beds, a rib needle from which a stitch is to be transferred and a plain needle to which the stitch is to be transferred, to approach one another to ensure the transfer of stitches from the rib needles to the plain needles.

13. In a knitting machine having two circular needle beds mounted for rotary movements, rib needles in one of the said needle beds and plain needles in the other said needle bed, means for controlling both sets of needles to knit rib fabric and one set of needles only to knit plain fabric, in combination with means to effect transfer of stitches from rib needles to plain needles, said means including an eccentric mounting of one needle bed with respect to the other, the construction and operation being such that transfer of the stitches from rib needles to plain needles is facilitated by the eccentric mounting of the two needle beds causing, during rotations of the two needle beds, a rib needle from which a stitch is to be transferred and a plain needle to which the stitch is to be transferred, to approach one another to ensure the transfer of stitches from the rib needles to the plain needles, in combination with means for imparting relative shogging movements to the needle bed preparatory to stitch transfer.

14. In a knitting machine having two circular needle beds mounted for rotary movements, rib needles in one of the said needle beds and plain needles in the other said needle bed, means for controlling both sets of needles to knit rib fabric and one set of needles only to knit plain fabric, in combination with means to effect transfer of stitches from rib needles to plain needles, said means including an eccentric mounting of one needle bed with respect to the other, the construction and operation being such that transfer of the stitches from rib needles to plain needles is facilitated by the eccentric mounting of the two needle beds causing, during rotations of the two needle beds, a rib needle from which a stitch is to be transferred and a plain needle to which the stitch is to be transferred, to ap-

proach one another to ensure the transfer of stitches from the rib needles to the plain needles, and means acting upon the stitches to open the same and facilitate entry of the plain needles.

- 5 15. In a knitting machine having two circular needle beds mounted for rotary movements, rib needles in one of the said needle beds and plain needles in the other said needle bed, means for controlling both sets of needles to knit rib fabric and one set of needles only to knit plain fabric, in combination with means to effect transfer of stitches from rib needles to plain needles, said means including an eccentric mounting of one needle bed with respect to the other, the construction and operation being such that transfer of the stitches from rib needles to plain needles is facilitated by the eccentric mounting of the two needle beds causing, during rotations of the two needle beds, a rib needle from which a stitch is to be transferred and a plain needle to which the stitch is to be transferred, to approach one another to ensure the transfer of stitches from the rib needles to the plain needles, and means acting upon the stitches to open the same and facilitate entry of the plain needles, in combination with means for imparting relative shogging movements to the needle bed preparatory to stitch transfer.

- 10 16. A method of transferring rib stitches to or from plain stitches, said method including knitting rib fabric upon two sets of opposed needles, retracting the needles of one set, knitting one or more courses upon the needles of the other set, imparting a relative shogging movement to the two sets of needles and then transferring stitches from the theretofore retracted needles to the needles of the other set.

- 15 17. A method of transferring rib stitches to or from plain stitches, said method including the opening of stitches to be transferred from one set of needles, and the movement of other needles to which the stitches are to be transferred through the opened loops, and ensuring the entry of the said other needles through the opened loops by causing the said needles and the needles first mentioned to approach one another.

- 20 18. In a knitting machine the combination of a set of dial needles, a set of cylinder needles, the dial needles being provided in alternating opposed relation with respect to the cylinder needles, said cylinder needles being divided into a long butt section and a short butt section, a set of jacks having butts at one level, said jacks being in alternating relation below the cylinder needles for elevating them and being divided into long butts and short butts directly below the long and short butts of the cylinder needles with which they are, respectively associated, another set of jacks alternating with the first mentioned jacks and being disposed respectively in cooperating relation below the remainder of the cylinder needles, said last mentioned set of jacks having butts at a level other than the level of the first mentioned jacks and said second set of jacks being divided into long and short butts and cam means for actuating the dial needles, cylinder needles and said sets of jacks for knitting plain fabric, rib fabric and automatically transferring the stitch loops from the dial needles to the cylinder needles.

- 25 19. In a knitting machine the combination of a set of dial needles, a set of cylinder needles, the dial needles being provided in alternating opposed relation with respect to the cylinder needles, said cylinder needles being divided into

a long butt section and a short butt section, a set of jacks having butts at one level, said jacks being in alternating relation below the cylinder needles for elevating them and being divided into long butts and short butts directly below the long and short butts of the cylinder needles with which they are respectively associated, another set of jacks alternating with the first mentioned jacks and being disposed respectively in cooperating relation below the remainder of the cylinder needles, said last mentioned set of jacks having butts at a level other than the level of the first mentioned jacks and said second set of jacks being divided into long and short butts and cam means for actuating the dial needles, cylinder needles and said sets of jacks for knitting plain fabric, rib fabric and automatically effecting a transfer from rib fabric to plain fabric.

20. In a knitting machine the combination of a set of dial needles, a set of cylinder needles, the dial needles being provided in alternating opposed relation with respect to the cylinder needles, said cylinder needles being divided into a long butt section and a short butt section, a set of jacks having butts at one level, said jacks being in alternating relation below the cylinder needles for elevating them and being divided into long butts and short butts directly below the long and short butts of the cylinder needles with which they are respectively associated, another set of jacks alternating with the first mentioned jacks and being disposed respectively in cooperating relation below the remainder of the cylinder needles, said last mentioned set of jacks having butts at a level other than the level of the first mentioned jacks and said second set of jacks being divided into long and short butts and cam means for actuating the dial needles, cylinder needles and said sets of jacks for knitting plain fabric, rib fabric and automatically effecting a transfer from one type of fabric to the other.

21. A circular independent needle knitting machine having dial needles and cylinder nee-

dles, means for controlling the movements of the dial and cylinder needles to knit rib fabric, means for controlling the movements of the cylinder needles only to knit plain fabric in continuation of the rib fabric, the transition from rib fabric to plain fabric being effected by causing stitches on the dial needles to be transferred to cylinder needles, in combination with means for causing the cylinder needles that knit rib fabric in conjunction with the dial needles, to knit one or more plain courses prior to the mentioned transition from rib fabric to plain fabric.

22. In a knitting machine the combination of a set of dial needles, a set of cylinder needles, the dial needles being arranged in alternating opposed relation with respect to the cylinder needles, said cylinder needles being divided into a long butt section and a short butt section, a set of jacks having butts on one level, said jacks being in alternating relation beneath the cylinder needles for elevating them, a plural number of said jacks companion to the first short butt needles having long butts, the remaining jacks companion to the said short butt needles having short butts, a plural number of the next adjacent jacks beneath the long butt needles having long butts and the remaining jacks beneath the long butt needles having short butts, another set of jacks alternating with the first mentioned jacks and being disposed respectively in cooperating relation below the remainder of the cylinder needles, said last mentioned set of jacks having butts at a level other than the level of the first mentioned jacks and said second set of jacks being divided into long and short butts and cams means for actuating the dial needles, cylinder needles and said set of jacks for knitting plain fabric, rib fabric and automatically effecting a transfer from rib fabric to plain fabric.
